UNITED STATES PATENT OFFICE.

OSCAR KALLANDER, OF NORTH TONAWANDA, NEW YORK.

DESIGN FOR A TOOTHBRUSH-HOLDER OR SIMILAR TOILET ARTICLE.

54,752.

Specification for Design.

Patented Mar. 23, 1920.

Application filed September 29, 1919. Serial No. 327,328. Term of patent 7 years.

To all whom it may concern:

Be it known that I, OSCAR KALLANDER, a citizen of the United States, residing at North Tonawanda, in the county of Niagara and State of New York, have invented a new, original, and ornamental Design for a Toothbrush-Holder or Similar Toilet Article, of which the following is a specification, reference being had to the accompanying drawings, forming a part thereof.

Fig. 2 is a side elevation thereof.

I claim:

The ornamental design for a toothbrush holder or similar toilet article, as shown.

OSCAR KALLANDER.
